UNITED STATES PATENT OFFICE.

GERARD NUESELL, OF BROOKLYN, NEW YORK.

INTERNAL-COMBUSTION ENGINE.

Application filed November 19, 1926. Serial No. 149,415.

This invention relates to improvements in internal combustion engines.

The primary object of the invention resides in an internal combustion engine of the 5 fourcycle type which is greatly simplified by the elimination of the crank shaft, cam shafts and fly wheel now commonly used in engines of this kind, thereby providing a simple and smooth running engine.

10 Another object of the invention is to provide an internal combustion engine of the V-type, that is, an engine having opposed cylinders disposed at right angle to each other, and which engine may be constructed 15 of any number of cylinders, and which cylinders fire on each revolution of the engine shaft but at different intervals, whereby an even power is produced.

A further object of the invention resides 20 in the construction of an engine having a straight engine shaft on which a cam is mounted for actuating the pistons at proper intervals, while cams for operating the inlet and exhaust valves, and the ignition system 25 are also mounted on said shaft.

With these and other objects in view, the invention resides in certain novel construction and combination and arrangement of parts, the essential features of which are 30 hereinafter fully described, are particularly pointed out in the appended claims, and are illustrated in the accompanying drawing, in which:—

Figure 1 is a vertical transverse sectional 35 view through my improved engine.

Figure 2 is a vertical sectional view on the line 2—2 of Figure 1.

Figure 3 is an enlarged detail sectional 40 view on the line 3—3 of Figure 1.

Figure 4 is a perspective view of the engine shaft with the cams mounted thereon.

Figure 5 is a detail perspective view of the piston.

Figure 6 is an enlarged detail view of the 45 ignition operating means.

Referring more particularly to the drawings, the reference numeral 10 designates my improved engine in its entirety, and which includes a pair of cylinders 11 and 12 disposed at right angle to each other as shown 50 in Figure 1 of the drawings, and which engines are known as the V-type. The two cylinders are identical in construction so that a description of one will suffice for the other.

55 Each cylinder is enclosed by a water jacket 13, while both cylinders open into a single

casing 14, within which an engine shaft 15 is journaled for rotation. Fixed to the shaft 15 is an eight-shaped cam 16 which is provided with a groove or track 17 which 6 opens on to the periphery of the cam through a slot 18. The track is of a shape corresponding to the shape of the periphery of the cam.

Slidable within each cylinder is a piston 19 which includes a piston head 20, a piston rod 21 rigidly secured to the underside of said head, while the free end of the piston rod is pivotally connected to a link 22 which extends through the slot 18 and carries sets 70 of rollers 23 and 24 for respective engagement with the outer periphery of the cam 16 and with the inner walls of the groove or track 17. The walls of the groove 17 prevent the accidental upward movement of the piston as the high point of the cam engages the set of rollers 23, as it will be appreciated that the centrifugal force of the cam tends to throw the piston upward. The piston stroke is 75 controlled by the shape of the outer periphery of the cam 16 and the walls of the recess 17. The cam is so shaped that the high spots are diametrically opposed so as to lift the piston twice on each revolution of the shaft 15, that is, on the compression stroke and the exhaust 80 stroke, while the low spots of the cam permit of the two downward strokes of the piston on each revolution of the shaft 15, namely the power stroke, and the intake stroke. The cylinders 11 and 12 are so disposed that when 85 the piston of one cylinder is on its upward stroke, the piston of the other cylinder is on its downward stroke. However, if a multiple of cylinders are placed side by side and all connected with the same engine shaft, a 90 steady and smooth running engine will be provided, as the cylinders will be timed to explode at successive intervals.

For guiding the piston on its upward and downward strokes, I provide rails 25 which 100 extend from the underside of the piston head 20 parallel to the side walls of the cylinder and which are disposed on opposite sides of the piston rod 21. The rails extend below the axis of rollers 23 and engage rollers 26 105 journaled in brackets extending from the inner walls of the casing 14. The rails 25 are braced by a cross arm 27 and serve to relieve the lateral strain on the piston when in a downward position.

110 Each cylinder is provided with an intake pipe 27' and an exhaust pipe 28, controlled

respectively by inlet and exhaust valves 29 and 30. A valve stem 31 extends from the inlet valve to a point in the path of movement of the peripheral edge of a cam 32 fixedly mounted on the shaft 15 at one side of the cam 16, the high spot of which is so arranged as to open the inlet port in the valve by lifting the valve stem at the required timed. A spring 33 tends to normally keep the inlet valve in a seated or closed position. A cam 34 is disposed on the opposite side of the cam 16 and is also fixed to the shaft 15. The high spot of the cam 34 is adapted to lift the valve stem 35 of the exhaust valve 30, to unseat the valve 30 at the proper time to permit the exhaust gases to escape through the exhaust pipe 28. A spring 36 tends to keep the exhaust valve 30 in a normally seated position.

20 The cylinders are provided with spark plugs 37 which are adapted to fire upon the limit of the upward movement of the piston on the compression stroke, in which the firing is controlled by cams 38 mounted on the shaft 15 and disposed beside the cams 32. Each cam has a high spot which serves to lift a rod 39 which is slidably mounted in the casing 14 and which rod has one of its ends disposed in the path of movement of the cam 38. The rod is normally held down against the cam by a spring 40 but upon upward movement, the same engages the end of a contact rocker arm 41, to swing the same into engagement with a stationary contact 42. The contact arm and the contact 42 are arranged in an electric circuit 43 with the spark plug of the respective cylinder to cause the circuit to be closed at the proper time to produce a spark within the cylinder.

40 As the high spot of the cam 38 clears the rod 39, the spring 40 moves the rod down and opens the circuit as will be readily understood.

45 In operation, the gas is taken into the cylinder upon the downward movement of the piston, at which time one of the high spots of the cam 16 is moving away from the rollers 23, and the high spot of the intake cam 32 is lifting the intake valve 29 off its seat. As the piston moves downward by reason of the low spots on the cam 16, the valve 29 closes, and as the other high point of the cam 16 gradually engages the rollers 23, the piston is moved upward to compress the charge of gas. Both the intake valve 29 and the exhaust valve 30 are in a closed position. As the other low spot of the cam 16 engages the rollers 23, the piston is in a position to move downward at which time 55 the ignition system is operated by the cam 38 to produce a spark at the spark plug, thereby causing an explosion of the gases within the cylinder. The piston moves downward and on its next upward stroke, 60 the cam 34 opens the exhaust valve 30 and

permits the exhaust gases to escape through the exhaust pipe 28. I have only described the operation of one of the cylinders, but it will be appreciated that the other cylinders operate in a like manner but in different 70 timed relation with respect to the other cylinders.

The casing 14 is filled with lubricating oil, and the said oil is picked up by cups 44 provided on the side faces of the cams for 75 splashing the oil over the working parts disposed within the casing.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claims. 85

What is claimed as new is:—

1. An internal combustion engine comprising a cylinder, a piston head slidable within said cylinder, a rotatable engine shaft, a figure eight shaped cam mounted on said engine shaft, a piston rod extending from said piston head, rollers carried by the free end of said piston rod and engaging the periphery of said cam, rails carried by said piston head and rollers engaging said rails for guiding said piston head during its reciprocation. 90

2. An internal combustion engine comprising a cylinder, a piston head slidable within said cylinder, a rotatable engine shaft, a figure eight shaped cam mounted on said engine shaft, a piston rod extending from said piston head, and rollers carried by the free end of said piston rod and engaging the periphery of said cam, said cam having a groove provided therein of a shape corresponding to the shape of the periphery of said cam and communicating therewith, a link pivotally connected to the free end of said piston rod, and rollers carried by said link and movable in said groove. 100

3. In an internal combustion engine, the combination of a cylinder, a piston reciprocable therein, and means for guiding said piston during its reciprocation, said means including rails carried by said pistons, and rollers engagng said rails. 115

4. In an internal combustion engine, the combination of a cylinder, a piston head reciprocable therein, a piston rod extending from said piston head, rails extending from said piston head on opposite sides of said piston rod, and rollers engageable with said rails, substantially as and for the purpose specified. 120

In testimony whereof I have affixed my signature.
